UNITED STATES PATENT OFFICE.

GEORGE J. WELTER, OF TIFFIN, OHIO.

PUMP.

Application filed May 13, 1925. Serial No. 30,011.

This invention relates to pumps and the primary object is to provide an easily operated double-acting pump by the use of which liquid may be drawn from a source of supply and delivered at a point of use in a continuous stream. The invention also has for its object the provision of means whereby the pressure in the pump may be noted at all times and will be maintained substantially uniform. Another object of the invention is to provide means whereby liquid which may accumulate in some of the pump passages will be returned to the inlet end of the pump so as to relieve the pressure and prevent waste of the liquid. Other objects of the invention will appear incidentally in the course of the following description, and the invention resides in certain novel features which will be particularly pointed out in the appended claims.

In the drawings:

Figure 1 is a side elevation of a pump embodying my invention;

Fig. 2 is a vertical longitudinal section through the cylinder;

Fig. 3 is a transverse vertical section on the line 3-3 of Fig. 1;

Fig. 4 is a transverse vertical section on the line 4-4 of Fig. 1;

Fig. 5 is an end view of a portion of the receiving or intake end of the pump;

Fig. 6 is a vertical section on the line 6-6 of Fig. 1, and

Fig. 7 is a transverse section on the line 7-7 of Fig. 1.

In the drawings, the reference numeral 1 indicates a bed plate which may be of any approved form and dimensions and is provided at one end with a post 2 having a bearing formed longitudinally through its upper end, the said bearing being lined by a bushing 3 to which lubricant may be supplied from an oil cup 4 and being adapted to receive and support and guide the outer end of the piston rod 5. Adjacent the post 2 an opening is provided through the bed plate 1 and on the under side of the bed plate adjacent the ends of the said opening are formed bosses 6 adapted to receive and retain a fulcrum pin 7 whereby the operating lever 8 may be supported for rocking

movement. The lever 8 may conveniently be a wooden bar of any approved length but is not mounted directly upon the fulcrum pin 7. To properly mount the lever upon the said fulcrum pin, the lower tapered end 9 thereof is fitted within a socket 10 which, as shown most clearly in Figs. 2 and 7, consists of mating members 11 having their bores or channels 12 downwardly tapered so that the lower tapered end of the lever may fit snugly therein. To secure the socket members in snugly clamping relation to the lever, clamping bolts 13 are fitted through the upper ends of the socket members and serve to firmly secure them together in an obvious manner. Below the lever, a bolt 14 is inserted through the socket members and through a spacing sleeve 15 disposed between the said members so that the spaced relation of the members will be maintained and their tendency to bend under strain will be counteracted. A similar bolt 16 and spacer sleeve 17 is provided near the lower ends of the socket members and the lower extremities of said members are flared to extend through the opening in the bed plate and are provided below the opening with ears 18 encircling the fulcrum pin 7 so that the lever may rock upon said pin. The socket members, of course, pass at opposite sides of the piston rod 5 and, between the said members, a sleeve 19 is fitted upon the piston rod and is secured thereto by a pin 20 inserted diametrically through the sleeve and the rod, as clearly shown in Fig. 2. The said sleeve is provided on its sides with trunnions 21 which play in slightly elongated openings 22 in the lever whereby, when the lever is oscillated, a reciprocatory movement will be imparted to the piston rod without causing binding of the lever upon the rod or the fulcrum sleeve.

Upon the bed plate near the end thereof remote from the post 2 are erected and secured the heads 23 and 24 which are of very similar construction and have their opposed faces recessed, as indicated at 25, to receive the ends of the cylinder 26. Packing 27 of any approved type is placed within the recesses 25 against the ends of the cylinder so that, when the parts are secured together,

leak-proof joints will be provided. To secure the cylinder in engagement with the respective heads, clamping bolts 28 are inserted through lugs or bosses 29 provided therefor upon the respective heads and equipped with nuts whereby, when the nuts are turned home, the heads will be firmly clamped together against the ends of the cylinder. Within the cylinder is provided a piston consisting of a central disk 30, against the opposite faces of which are placed cup washers 31 of any suitable flexible material, other washers 32 of metal or other rigid material being placed against the outer faces of the flexible cup washers. The piston rod 5 extends through a gland 33 provided therefor upon the head 23 and terminates within the cylinder, as will be understood upon reference to Fig. 2. The end of the piston rod 20 is reduced, as shown at 34, thereby providing an annular shoulder 35 fitting against the adjacent washer 32 and being equipped at its extremity with a nut 36 arranged to be turned home against the opposite washer 32 whereby the piston will be firmly clamped upon the piston rod. It will be, of course, noted that the flexible cup washers 31 fit closely against the wall of the cylinder so that they prevent the flow of liquid past the piston and, consequently, they will effectually operate to draw liquid into the cylinder upon one stroke and will then force the liquid from the cylinder upon the opposite stroke. Both heads 23 and 24 are provided at their lower edges with lateral feet 37 adapted to rest flat upon the bed plate, and cap screws or bolts 38 are inserted through the several feet into the bed plate to rigidly secure the heads in place. It will be understood that the heads are assembled with the cylinder and the piston before being bolted to the bed plate and that the feet upon the respective heads have openings therethrough which are somewhat elongated to permit such slight adjustment of the heads longitudinally of the bed plate as may be necessary to effect the required rigid assemblage of all the parts.

The head 24 is the receiving head of the pump and its inner face is provided with a shallow recess 39 communicating with the recess 25 whereby the liquid may readily flow into and out of the cylinder. Above the said recess 39, the head has formed thereon a vertically disposed barrel or valve casting 40 having its bore 41 communicating directly with the recess 39 through the end of a transverse channel 42. The bore 41 is expanded in its upper portion to provide a beveled valve seat 43 and a disk valve 44 normally rests upon the said seat, being yieldably held thereto by a spring 45 arranged between the valve and a cap plug 46 threaded into the upper end of the barrel 40. An outlet port 47 is formed in the

side of the barrel 40 immediately above the valve seat 43 and this port opens directly into a nipple or elbow 48 formed upon the side of the barrel, as shown. In the end of the nipple or elbow 48 is secured one end of an outlet pipe 49, the opposite end of which is connected with the delivery pipe 50 through couplings 51, as shown clearly in Fig. 3. Between the ends of the pipe 49, an air chamber or equalizing dome 52 is mounted and is in constant communication with the interior of the pipe so that water which may rise within the dome will trap the air therein and, through the reacting pressure of the air, will be caused to flow from the delivery pipe 50 in an even constant stream. A pressure gage 53 of any approved form is mounted upon the dome 52 and is in communication with the interior of the same.

The transverse channel 42 extends across the bottom or lower end of the barrel 40 and opens into an inlet barrel 54 formed upon the head 24 and having one end of the supply pipe 55 secured in its lower end. The channel 42 enters the barrel 54 immediately above the valve seat 56 formed therein, and a disk valve 57, corresponding to the valve 44, is yieldably held to said seat by a spring 58 corresponding to the spring 45 and held within the barrel by a cap plug 59. From the description thus far given, it will be seen that, when the piston moves away from the head 24, a partial vacuum will be formed between the same and the valves 44 and 57, as a result of which action the valve 44 will be held seated and the valve 57 will open under the pressure of the water against the tension of the spring 58. The water or other liquid will then obviously flow past the valve 57 through the channel 42 and enter the cylinder. Upon the reverse stroke of the piston, the liquid will be compressed against the valve 57 which will be thereupon seated and the pressure exerted through the liquid will lift the valve 44 from its seat, whereupon the liquid will pass out through the port 47 into the pipe 49 and thence flow through the delivery pipe to the point of use.

The head 23 is constructed with a shallow transverse channel 60 corresponding in all essential respects to the channel 42 of the head 24 whereby communication is established between the head 23 and the adjacent end of the cylinder. At one end, the channel 60 opens into the lower end of a barrel 61 in which is mounted a valve 62 corresponding in all respects to the valve 44 and held in place by a spring 63 and cap plug 64. Above the valve 62, the barrel 61 is provided with an outlet port 65 communicating directly with the bore of a boss 66 formed upon the side of the head and directed toward the opposite end of the cylinder. A pipe 67 has one end secured in

the said boss 66 and has its opposite end secured in a nipple 68 on the side of the elbow or coupling 48 on the head 24, thereby connecting the discharge sides of the two heads so that the liquid forced out by either stroke of the piston will be driven into the pipe 49 and thence flow to the delivery pipe 50. The head 23 is also formed with a barrel 69 having a valve seat 70 therein below the opposite end of the channel 60, and a valve 71 is yieldably held to the said seat by a spring 72 and cap plug 73. The barrel 69 extends to the lower portion of the head 23 and is then turned forwardly 15 to receive and be firmly connected with one end of a pipe 74 which extends forwardly and has its front end fitted in a nipple formed on the barrel 54 or the head 24 at the lower end of the said barrel 54. This pipe 20 74 constitutes the inlet pipe for the head 23 and it will thus be seen that upon either stroke of the piston liquid is drawn into one end of the cylinder through the head connected therewith and is simultaneously discharged from the opposite end of the cylinder through the adjacent head. I thus attain a constant flow through the delivery pipe and, as all of the outflowing liquid 25 must pass the pressure dome, the pressure or force of the discharging liquid will be practically uniform.

Connected with the lower coupling 51, by which the dome pipe 49 is connected to the discharge pipe 50, is an overflow pipe 75 which leads into a casing 76 which houses an overflow or pressure-regulating valve of any approved type. Extending from the lower side of the casing 76 is a drain pipe 77 which has a horizontal branch 78 extending into the barrel 54 at the lower end thereof. Should the pressure of the outflowing liquid rise above a predetermined point, the regulating valve will be opened and the excess liquid will then flow through the pipes 75, 77 and 78 back to the inlet end of the barrel 54 so that it will be returned to the circulating system while the strain upon the discharge pipe and the co-acting parts will be very effectually relieved.

From the foregoing description, taken in connection with the accompanying drawings, it will be seen that I have provided a very compact double-acting pump whereby liquid may be discharged under a considerable pressure without excessive strain upon the part of the operator. Moreover, while I have illustrated and specifically described a lever to be operated by hand for driving the pump, it will be understood that any approved means for reciprocating the piston and piston rod may be employed. The form of hand-operating mechanism herein shown and described is very efficient inasmuch as it is so mounted as to equalize the strain and thereby avoid bending or twisting of any of the parts and

it will operate directly upon the piston rod. Furthermore, it may be very easily and quickly assembled with the bed plate and the piston rod. Particular attention is invited to the fact that the valves which control the flow of liquid into and from the cylinder all operate automatically and are easily accessible inasmuch as, in order to remove any valve, it is necessary merely to withdraw the cap plug above the same, 70 whereupon the spring and the valve may be lifted from its seat and any cleaning or regrinding which may be needed may be performed without requiring dismantling of the entire pump. The respective heads and 75 the passages by which the liquid is directed to and from the ends of the cylinder may be formed by a single casting operation and the two heads and the cylinder may be very easily and quickly secured together in operative 80 relation and in such manner as to prevent leakage. It is also to be noted that the outer free end of the piston rod is supported and guided by the post upon the bed plate and, consequently, bending and binding of the 85 piston rod is not apt to occur. In the outer side of each head is a drain opening 79 which is closed by a screw plug 80 and the said opening communicates directly with the respective channels 42 and 60 to permit drainage 90 of the same when necessary.

Having thus described the invention, I claim:

1. A pump comprising an open-ended tubular cylinder, heads for the ends of said cylinder, each having its inner face formed with a recess constituting a seat to receive an adjacent end of the cylinder and a transversely extending pocket having its intermediate portion communicating with the cylinder, 100 valve chambers extending upwardly from the end portions of said pocket, one being formed with a depending inlet neck and the other with an outlet neck extending transversely therefrom intermediate its ends, 105 pipes connecting the necks of the valve chambers of one head with the necks of corresponding valve chambers of the other head, the ends of said pipes being removably engaged with the valve chamber necks, draw rods extending between and engaged with said heads to releasably retain the heads in engagement with the ends of said cylinder and pipes, upwardly opening valves in said valve chambers normally closed and controlling passage of fluid through the inlet and outlet necks, and removable closures for the upper ends of said valve chambers.

2. A pump comprising an open-ended tubular cylinder, heads for said cylinder, each head having its inner face formed with a seat to snugly receive an end portion of said cylinder and with a transversely extending shallow pocket having its intermediate portion communicating with the cylinder and

extended outwardly to form a neck portion formed with side arms, valve chambers extending upwardly from the end portions of said side arms, one chamber having an outlet neck extending transversely therefrom and the other extended downwardly to form an inlet neck, said necks being formed with side arms, pipes extending longitudinally of the cylinder at opposite sides thereof with their ends fitted into the side arms of said

necks to provide communication between said heads, draw bolts extending between and engaged with said heads to firmly but releasably hold the heads in operative engagement with the ends of said cylinder and pipes, and upwardly opening check valves in said chambers to control passage of fluid through the same. 15

In testimony whereof I affix my signature.

GEORGE J. WELTER. [L. S.]
